The ornamental design for a multi-position ladder bucket as shown and described.

DESCRIPTION

FIG. 1 is a perspective view of a ladder top cap multi-position ladder bucket showing our new design;

FIG. 2 is a top plan view thereof;

FIG. 3 is bottom plan view thereof;

FIG. 4 is a front elevational view thereof;

FIG. 5 is a rear elevational view thereof;

FIG. 6 is a right-side elevational view thereof; and,

FIG. 7 is a left-side elevational view thereof.

The broken lines shown in the figures define the bounds of the claimed design and form no part of the claimed design. The broken lines also show portions of the multi-position ladder bucket that form no part of the claimed design.
